UNITED STATES PATENT OFFICE.

JESSE SWEGLE, OF WALLA WALLA, WASHINGTON.

SIPHON-PUMP.

1,277,772.

Specification of Letters Patent. Patented Sept. 3, 1918.

Application filed March 30, 1918. Serial No. 225,722.

To all whom it may concern:

Be it known that I, JESSE SWEGLE, a citizen of the United States, residing at Walla Walla, in the county of Walla Walla and 5 State of Washington, have invented new and useful Improvements in Siphon-Pumps, of which the following is a specification.

This invention relates to improvements in siphon pumps, especially adapted for use 10 in siphoning gasoline from the tanks of automobiles but also adapted for use for other similar purposes, the object of the invention being to provide an improved siphon pump of this character which is simple in construction, is effective in operation, and 15 which can also be used as a squirt gun when desired.

With the above and other objects in view the invention consists in the construction, 20 combination and arrangement of devices hereinafter described and claimed.

In the accompanying drawings:—

Figure 1 is an elevation, partly in section, 25 of a siphon pump constructed and arranged in accordance with my invention.

Fig. 2 is a similar view of the same when arranged for use as a squirt gun.

The cylinder or barrel 1 of my improved siphon pump may be made of brass tubing 30 or any other suitable material, is closed at the lower end as at 2 and is open at the upper end and is provided in the upper end with a removable closure 3 which fits tightly therein. At a suitable distance from its 35 lower end the barrel is provided with a series of small inlet openings 4. Near its upper end and on one side the barrel is provided with a spout 5 to which a rubber hose 6 of suitable length and diameter is attached.

40 A plunger 7 is arranged to operate in the cylinder and comprises a pair of reversely turned leather or other suitable cups 8 which are secured between a pair of washers 9 and to the lower end of a plunger rod 10. Said 45 plunger rod extends up through the cylinder and also through a central opening in the closure 3 and is formed or provided with a handle 11 at its upper end. The bottom 2 of the cylinder is provided with an opening 12 of suitable diameter.

To use the siphon pump for siphoning gasoline from a tank which is nearly full the barrel is placed in the tank and the plunger is drawn to the upper end of the barrel. This creates a partial vacuum which 55 causes gasoline to be sucked up through the barrel and a siphonic flow to be started through the barrel and also through the hose 6, as will be understood.

When using a pump to siphon gasoline 60 from a tank nearly or partially empty the hose should be placed in the tank and extended to the bottom of same, and the plunger should be then pushed down to the bottom of the cylinder but not below the 65 openings at the bottom. This downward movement of the plunger draws the cylinder nearly full of gasoline. Then take the hose out of tank and place the barrel in and use the same as is stated in siphoning from 70 full tank.

To enable the siphon pump to be used also as a squirt gun, I provide a nozzle 13 at the lower end of a cap sleeve 14, which 75 cap sleeve can be screwed or otherwise detachably secured to the lower end and so as to close the openings 4.

Having thus described the invention, what is claimed as new is:—

The herein described pump for use as a 80 siphon pump and also for use as a squirt gun comprising a cylinder having an opening at the lower end and also having inlet openings spaced from the lower end, said cylinder being provided with a hose connected thereto at its upper end, a closure in the upper end of the cylinder having a central opening, a plunger arranged to operate in the cylinder, a rod for the plunger extending through and arranged to operate in the central opening of the closure, and a cap sleeve detachably secured to the lower end of the cylinder to close the inlet openings of the cylinder and provided with a 85 nozzle.

90 In testimony whereof I affix my signature.

JESSE SWEGLE.
